UNITED STATES PATENT OFFICE.

HUGH H. WHITEHEAD, OF ANNA MARIA, FLORIDA.

MECHANICAL MOVEMENT.

1,076,179.

Specification of Letters Patent.

Patented Oct. 21, 1913.

Application filed July 19, 1912. Serial No. 710,518.

To all whom it may concern:

Be it known that I, HUGH H. WHITEHEAD, a citizen of the United States, residing at Anna Maria, in the county of Manatee and State of Florida, have invented a new and useful Mechanical Movement, of which the following is a specification.

The present invention relates to improvements in mechanical movements, the primary object of the invention being the provision of means to convert a reciprocatory movement of the piston rod of an engine in which the usual form of crank shaft is dispensed with, and a rotary movement in a longitudinal shaft which is provided with the usual fly wheel, thus providing a means whereby the main driving shaft containing the fly wheel is rotated constantly in the desired direction and has imparted thereto any number of revolutions without regard to the number of reciprocations of the piston rod.

A further object of the present invention is the provision of a novel means whereby the rotation of the shaft may be readily reversed without interfering with the reciprocating movement of the piston rod.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a longitudinal sectional view through the complete engine. Fig. 2 is a section taken on line 2—2 of Fig. 1. Fig. 3 is a section on line 3—3 of Fig. 1. Fig. 4 is an enlarged sectional view through the ratchet gears for operating the spiral shaft. Fig. 5 is a detail view in top plan of the two gears, their carrying frame and the shaft. Fig. 6 is a detail view of one of the pawls for locking its gear against rotation.

Referring to the drawings, the numerals 1 and 1' designate the respective cylinders of the engine which as shown, are disposed horizontally and have mounted therein, the respective reciprocatory pistons 2 and 2', which are connected by means of the connecting rod 3. Connected intermediate of the ends of the rod 3 is a coupling 4 which carries thereby the rod 5 whose upper end is

provided with a hand grip 6 and extends through the elongated slot 7 of the engine casing C. The lower end of the rod 5 is forked as at 8, the purpose of which will presently appear. Disposed upon the respective inner faces of the cylinders and in the path to engage the rod 5, are the two spring cushions 9 and 9', which act as a cushioning means at the end of each respective stroke of the pistons 2 and 2'.

Mounted upon the base 10 are the two bearings 10' in which are journaled the main driven shaft 11 of the engine. The shaft is provided centrally of its length, as clearly shown in Fig. 1, with the two sets of spiral grooves 12 and 13. Mounted upon one end of the shaft 11, is the fly wheel 14, while disposed for sliding movement about the grooved portion of the shaft is a frame 15. This frame or casing 15 is connected rigidly to and is moved with the rod 5, the same being disposed within the forked end 8 of the said rod 5, as clearly shown in Fig. 2. The two gears or ratchet wheels 16—17, are mounted upon the spiral portion of the shaft 11, one of which is provided with the rib 18 fitting in the spiral 12, and the other of which is provided with the rib 19 fitting in the spiral 13 (Fig. 4). These gears are permitted normally to rotate, but it is desired that one shaft shall be rigid relatively to the carrying frame 15, while the other is free, and vice versa; and, in order to accomplish this the rod 20 is mounted in ports 21—21', and by means of the handle 22, the rod may be oscillated. Keyed upon the rod 20 and within and slidable with the casing 15, are the two pawls 23 and 24, which extend in opposite directions, one above each of gears or wheels 16 and 17, respectively. Thus by the manipulation of the rod 20, the pawl 23 is placed in engagement with the gear 16, and the pawl 24 is released from the gear 17. When in this position the reciprocation of the frame, with the gear 16, locked, will rotate the shaft 11 in one direction; and should it be desired to reverse the rotation of the shaft 11, the rod 20 is oscillated in the opposite direction to place the pawl 24 in engagement with the gear 17 and to release the pawl 23 from the gear 16. The gears 16 and 17 are provided with ball bearings 25 to reduce the friction at the wearing surfaces. It is also evident that a single way rotating shaft may be employed and that only one

gear 16 would be used, thus dispensing with the rod 20 and then having a single pawl 23.

Each of the respective cylinders 1 and 1' are provided with the carbureted air admitting port 36 at the base of each of the respective cylinders, the same being so disposed that upon the out-stroke of either one of the power pistons 2-2', a charge of carbureted air will be drawn into the cylinder 10 and upon the explosive stroke will be ejected through the port 38 into the chamber 39 and finally through the port 40 into the combustion chamber 41 of the cylinder 1 or 1'. The spark plug 42 is so timed as to explode 15 the compressed charge at the desired highest point of compression so that the burned gases will be expelled through the exhaust port 45 of the respective cylinders 1 and 1'.

From the foregoing description, taken in 20 connection with the drawings it is evident that by means of the mechanism connected to the shaft 11 and actuated by the rod 3 of the two power pistons 2-2', that the desired rotation will be imparted to the shaft 11 and 25 that the stroke of the respective pistons 2 or 2' may be increased to any degree so that a plurality of rotations to each reciprocation will be imparted to the shaft 11 and not a single rotation as is the case where the pistons are connected to a crank shaft through 30 a piston rod as is the usual custom.

It is also evident that by means of the mechanism controlled by the levers at the

end of the engine base, that the rotation of the shaft 11 may be reversed at any time 35 without affecting the reciprocation of the power pistons.

What is claimed is:

A mechanical movement, including a reciprocatory rod, a longitudinally disposed 40 rotatable shaft mounted parallel with said rod, said shaft having two spiral grooves intermediate of its ends, an arm connected to the reciprocatory rod and extending toward the shaft, a frame carried upon one end of 45 said arm and surrounding the shaft, two ratchet wheels mounted in said frame and having the teeth thereof disposed in opposite directions, each of said ratchet wheels being provided with a lug disposed to fit 50 within the respective grooves of the shaft, a manually oscillated rod disposed parallel to the grooved shaft, and two oppositely disposed pawls slidably keyed upon the rod and within the frame, whereby either pawl is 55 placed into engagement with its respective ratchet wheel for locking one wheel at a time against rotation.

In testimony that I claim the foregoing as my own, I have hereto affixed my signature 60 in the presence of two witnesses.

HUGH H. WHITEHEAD.
